UNITED STATES PATENT OFFICE.

LEWIS E. CURTIS, OF WARREN, OHIO, ASSIGNOR TO THE YOUNGSTOWN PRESSED STEEL COMPANY, A CORPORATION OF OHIO.

METAL-EXPANDING MACHINE.

Application filed January 5, 1924. Serial No. 684,643.

To all whom it may concern:

Be it known that I, LEWIS E. CURTIS, a citizen of the United States, residing at Warren, in the county of Trumbull and State 5 of Ohio, have invented a new and useful Improvement in Metal-Expanding Machines, of which the following is a specification.

This invention relates to machines for expanding blanks of sheet metal which have 10 been previously slotted and is an improvement on the machine shown and described in my previous Patent No. 1,011,588, granted December 12, 1911. The invention is fully described in the following specification and 15 shown in the accompanying drawings in which:

Figure 1 is a plan view of an expanding machine embodying the invention;

Fig. 2 is a side elevation of the same;

Fig. 3 is a central longitudinal section 20 through the machine;

Fig. 4 is an enlarged side elevation of an expanding arm showing the side plates removed;

Fig. 5 is a view of the lower half of the 25 expander arm as viewed on the line 5 of Fig. 4;

Fig. 6 is a similar view of the upper half of the expander arm viewed on the line 6 30 of Fig. 4;

Fig. 7 is a transverse section through an 35 expanding arm on the line 7 of Fig. 4;

Figs. 8, 9 and 10 are diagrammatic sectional views showing the relative position of the 40 chains of the expander arms at various positions along these arms;

Fig. 11 is an enlarged perspective of a 45 section of the edge of the bed or way showing the ledges over which the blank is stretched;

Fig. 12 shows a section of the slotted blank 50 previous to expanding; and

Fig. 13 is a similar view of the section of the metal as it is expanded.

The embodiment illustrated comprises a machine having a frame 15 above which is a table 16 along which the previously slotted blanks as shown in Fig. 12, are fed endwise to the machine. A shaft 17 is journalled in 55 suitable bearings in the main frame and carries a pulley 18 by which it is driven from any suitable source of power. The pinion 19 on this shaft meshes with a gear 20 on the shaft 21. The gear 22 likewise on this

shaft meshes on the gear 23 on the shaft 24 55 which in turn carries a gear 25 which meshes with the gear 26. The latter gear drives a sprocket 27 which through the chain 28 drives a similar sprocket 29 which is journaled in the outer end of the expander 60 arm 30.

The similar expanding arms 30 and 31 are pivotally mounted at 32 on the machine and are made diverging on being set above and extend below the line of travel of the 65 blank along the table 16.

These expander arms are substantial duplicates so that a description of one will suffice for both. The upper arm 30 is composed of two castings 33 and 34 secured together 70 by means of bolts 34^a. The upper casting 33 carries a chain 35 which passes over sprockets 36 and 37; the former being carried on a shaft 38 on which is keyed the sprocket 29. The chain 35 has a longitudinally grooved face 35^b which is adapted to engage the indentations in the blank A which are caused by the slitting cutters. For this reason these longitudinal grooves are preferably of a width corresponding to the width 75 of the strands of the blank with which they co-operate.

A series of rollers 39 are journalled on stub shafts 40 which are carried in opposite positions on shafts 41 as shown in Figs. 6 85 and 7. The shaft 41 is journalled in the casting 33 and at its far end has pinned thereon a lever 42. A spring 43 acts upon the end of this lever and exerts a constant pressure upon the rollers 39, which pressure is transmitted to the chain 35 and causes it to press down on the blank A as it passes through, thereby firmly retaining the same against lateral movement.

The lower casting 34 carries a chain 44 95 which may suitably have a smooth face and which passes around sprockets 45 and 46, the former being keyed to a shaft 47 which is driven by suitable gears 48 and 49 from the shaft 38.

The grooved chain 35 lies at an angle to the chain 44 as shown in Figs. 1, 5 and 6 and overlies it during a large portion of its length of travel. This is illustrated in Figs. 8, 9 and 10, the first showing the relative 105 position of the chains of the two diverging expander arms at the time the blank enters these arms. At the right of each of these

figures the chains 35 and 44 are those that have just been described, while the chains 35^a and 44^a at the left are similar chains of the other expander arm 31.

5 It will be noted that in all three of Figs. 8, 9 and 10 the chains 35 and 35^a while diverging in a vertical plane have kept the same relative position laterally, while the chains 44 and 44^a have diverged both vertically and laterally. Alongside the chain 44 is a bar 50 having series of steps or shoulders 51 disposed as to correspond to the length and width of the slotted portions of the blank A. Thus as the blank passes 10 along from the position shown in Fig. 8 to the position shown in Figs. 9 and 10, the blank A will have that portion of it between the edges of the bars or edge plates 50 and 50^a deflected and expanded as shown 15 at B in these figures and in Fig. 13. During the time the blank A is passing from the position shown in Fig. 8 to that of Fig. 9 and later to that of Fig. 10, the unexpanded portion of the blank is retained between the chain 35 and the chain 44 and the bar 50. At the same time the chains 35 and 44 carry the blank A along, the blank A being drawn across and over the bar 50. As it passes over the bar 50 the various 20 strands pass over the steps or notches 51, and are deflected downwardly thereover, being thereby opened to expand the metal to the form shown in Fig. 13.

While I have shown and described certain embodiments of my invention, it is to be understood that it is capable of many modifications. Changes therefore in the construction and arrangement may be made 25 without departing from the spirit and scope

of the invention as disclosed in the appended claims, in which it is my intention to claim all novelty inherent in my invention as broadly as possible in view of the prior art.

I claim:

1. In a machine for expanding previously slotted metal blanks, a pair of diverging expanding arms, each having a chain for feeding said blanks along said arm including means for guiding said blanks along said arm, a stepped edge plate lying at an angle across said chain and a second chain operating along said edge plate and at substantially the level of said edge plate.

2. In a machine for expanding previously slotted metal blanks, an expander having a stepped edge plate, a chain movable along said edge plate, a movable chain opposing the first mentioned chain and edge plate, means for feeding a blank between the chains, whereby the chains are caused to carry the blank forward at an angle to the edge plate, and means for deflecting the strands of the blank over the shoulders of the edge plate.

3. In a machine for expanding previously slotted metal blanks, a pair of diverging expanding arms, each having a stepped edge plate, a chain movable along said edge plate and a movable chain opposing the first mentioned chain and the edge plate, means for feeding a blank to the expander arms, whereby each half of the blank is carried forward by the chains of the expander arms at an angle to the edge plate thereon, and thereby deflecting the strands of the blank over the shoulders of the edge plates.

LEWIS E. CURTIS.
